UNITED STATES PATENT OFFICE.

JOHN B. PEARSON, OF STONEHAM, MASSACHUSETTS, ASSIGNOR OF ONE-HALF TO ALBERT W. FULLER, OF CLIFTONDALE, MASSACHUSETTS.

LIGHT-DISTRIBUTING DEVICE.

No. 858,620.

Specification of Letters Patent.

Patented July 2, 1907.

Application filed May 5, 1906. Serial No. 315,321.

To all whom it may concern:

Be it known that I, JOHN B. PEARSON, of Stoneham, in the county of Middlesex and State of Massachusetts, a citizen of the United States, have invented a new and useful Improvement in Light-Distributing Devices, of which the following is a full, clear, and exact description, reference being had to the accompanying drawings, forming a part of this specification, in explaining its nature.

- 10 The occasion very often arises where, if rays of light were properly concentrated and distributed, the rays from one lamp or light might as well or even better accomplish the effect of more. This is especially true of offices where there are desks, or of shops where there is 15 machinery. In such places it is necessary to throw a strong light upon that portion of the desk or of the machine where work is going on, and the custom has been to provide the shop or the office with a number of lights.
- 20 It is accordingly the object of my invention to provide a device which by properly concentrating and distributing the rays of light from one lamp enables it to accomplish the effect of more.

My invention can best be seen and understood by 25 reference to the drawings, in which—

Figure 1 shows the device in side elevation. Fig. 2 shows a vertical section thereof. Fig. 3 shows the reflector portion of the device in plan. Fig. 4 shows in vertical section a modified form of reflector made adjustable in construction, and Fig. 5 shows the same 30 in plan.

In the drawings:—A represents a shell or casing which is preferably cylindrical in shape and of material through which light cannot pass. On top of this 35 casing is mounted a head or dome A¹ having inside the same a reflecting surface a. Within the casing, beneath the interior reflecting surface of the dome, is a lamp A². The lamp shown is a common gas lamp having a mantle, although any kind of lighting device or 40 medium may be used. These parts are assembled and supported in the following manner:—

A³ represents a ring which connects with some suitable fixture of support as a gas pipe A⁴, connection being made in a manner hereinafter explained. This 45 ring fits outside the casing A and said casing is attached to the ring in such manner as to be supported by it. I prefer that the connection be such as to permit the casing being turned and also a connection permitting of the casing being easily detached from the ring without disturbing the other parts. Accordingly the ring is shown 50 having an inner annular flange a¹. This flange has in it openings a² which permit the entrance of out-turned flanges a³ extending from the upper part of the casing so that after these flanges on the casing have been passed

through these openings, then upon slightly turning the 55 casing, its flanges a³ will rest upon the upper surface of the flange a¹ of the ring, which accordingly acts as a support for the casing. This connection not only permits of the casing being very easily detached from the ring, but it also permits of the casing being turned. In order 60 that the casing may be held firmly in position after it has been connected with the ring and turned to any point of adjusted position, a screw a⁴ may be passed through the ring into the casing.

As for the dome or head A¹, this is supported by the 65 ring by simply resting upon it, the ring having a supporting ledge a⁵ upon which the dome or head rests and an annular shoulder a⁶ which prevents the head from becoming displaced.

As for the lamp A² inside the casing, this, also, is supported independently of the casing and the head or dome, in the following manner:—In the first place it is to be observed that the supporting ring A³ connects with the fixture or gas pipe A⁴ by means of a connecting coupling or block a⁷. This block may be formed integral 75 with the ring or otherwise connected thereto. The pipe or fixture A⁴ makes a threaded connection with this block as does also a pipe or fixture a⁸ supporting the lamp A², the passages through the pipes A⁴ and a⁸ being connected through the block. Accordingly it is to be 80 noted that the lamp A² is supported by the ring and connection is made through it or the block attached to it for the passage of the gas or even for the entry of wires, in case an electric light is used, independently of the casing and its dome.

At the lower end of the casing A, so as to lie in a position beneath the reflecting surface of the dome, is what 85 may be termed a reflector A⁵. This reflector consists of a supporting base a⁹ having one or more reflecting surfaces or faces a¹⁰ so arranged in relative disposition to 90 the reflecting surface a of the dome that the rays of light striking the reflecting surface of the dome will be reflected thereby to the surfaces or faces of the reflector and from these surfaces be reflected to points outside the casing. In this connection it is to be noted that 95 the interior reflecting surface a of the dome is made up, preferably, of a number of reflecting panels in order that the direction of the rays of light from the lamp may be changed to properly fall upon the surfaces or faces of the reflector.

The reflector is preferably made pyramidal in shape so as to have a plurality of the reflecting surfaces or faces a¹⁰, whereby the rays of light may be thrown in different directions, it being noted, of course, that the lower portion of the casing A is cut away in part forming 101 openings which permit of the passage of the rays of light from the surfaces or faces of the reflector to points outside the casing, the rays of light, however, being

shut off from passing in a direction intermediate these reflecting surfaces, and in fact, from extending in any other direction than that in which the rays are extending from said surfaces, thereby assisting in the concentration of the light upon the object upon which the light is thrown and shading its surroundings, or in other words, keeping the light only on the work and out of the eyes of the one working.

The reflector A⁵ is preferably made a part detachable from the casing, being supported to the lower edge thereof by means of connecting chains a¹¹ or other means of connection. As said before, there may be as many of the reflecting surfaces or faces a¹⁰ as may be required. The inclination and angular arrangement of the surfaces or faces will, of course, depend upon the location of the surrounding objects upon which the light from the lamp is to be thrown. If the objects are arranged in rectangular order of arrangement relatively to the reflector, then its reflecting surfaces or faces will be rectangularly arranged and with the same angle of inclination. If, however, the objects are irregularly arranged with respect to the reflector, then its reflecting surfaces or faces will be correspondingly changed in order that the light may be properly projected upon each of the objects.

Inasmuch as objects surrounding the lighting device are generally irregularly arranged, I have provided means whereby the surfaces or faces of the reflector may be changed, in order that the angle of their reflection 30 may be varied, whereby the light may be thrown upon the various irregularly disposed surrounding objects. This construction I have shown in Fig. 4 where there is shown a reflector A⁶ having a number of reflecting surfaces a¹² independently supported. The reflecting surfaces or faces a¹² are preferably triangular in shape and they are separately supported in the following manner:—

The base portion of the reflector comprises an annular ring a¹³ which is secured to the bottom part of the 40 casing by chains a¹¹ or other means of support. Across the ring extend supporting webs a¹⁴; a¹⁵. In these webs or bars are formed slots a¹⁶. In these slots run slides a¹⁷ which are held at different points of adjusted position by means of thumb screws a¹⁸. Fastened to these 45 slides by jointed connections a¹⁹ are arms a²⁰ which support the surfaces or faces of the reflector by forming a ball and socket connection a²¹ with plates a²² bearing the same. By this adjustable arrangement the surfaces or faces of the reflector can be independently adjusted to assume practically any desired angular position 50 whereby the light from the reflector may be thrown or projected to cover objects however irregularly arranged.

Having thus fully described my invention, I claim 55 and desire to secure by Letters Patent of the United States:—

1. A device of the character specified having a non-transparent casing with separate openings in the sides thereof and a reflector contained within said casing having

faces in line with said openings in the sides of the casing 60 and upon which faces the rays of light from a lamp supported within the casing are directed to fall and be laterally reflected through the openings in said casing to points outside the same.

2. In a device of the character specified, a casing having 65 separate openings in the sides thereof, a dome to said casing having an interior reflecting surface, a reflector inside said casing below said reflecting surface of the dome, said reflector having reflecting surfaces adjacent to said openings in the casing and so arranged that rays of light 70 from a lamp inside said casing falling upon the reflecting surface of the dome may be reflected onto the reflecting surfaces of said reflector and thereby be thrown out laterally through said openings formed in said casing.

3. In a device of the character specified, a non-transparent casing the bottom of which is cut away in part to form separate openings with portions of the casing intermediate said openings, a dome to said casing having an interior reflecting surface, a reflector inside said casing below said reflecting surface of the dome, said reflector having reflecting surfaces adjacent to said openings in the casing so arranged that rays of light from a lamp inside 80 said casing falling upon the reflecting surface of the dome may be reflected thereby onto the reflecting surfaces of said reflector and thereby be thrown out laterally through 85 said openings in the casing, and means for supporting said reflector from the bottom of said casing.

4. In a device of the character specified, a non-transparent casing having an opening or openings therein, a reflector inside said casing having one or more reflecting 90 surfaces upon which rays of light from a lamp inside said casing are adapted to fall and be reflected to a point or points outside said casing, and means supporting said casing whereby it may be rotated.

5. In a device of the character specified, a non-transparent casing having separate openings in the sides thereof, a ring from which said casing hangs dependent, a dome to said casing mounted upon said ring, said dome having an interior reflecting surface, and a reflector inside said casing below said reflecting surface of the dome, said reflector having reflecting surfaces adjacent to said openings in the casing whereby rays of light from a lamp inside 100 said casing intermediate said reflector and dome falling upon the reflecting surface of the dome may be reflected onto the reflecting surfaces of said reflector and thereby 105 be thrown out laterally through the openings in the sides of the casing.

6. A device of the character specified having a casing, a ring having connection with some fixture of support, means for detachably attaching said casing to said ring 110 whereby it may be turned thereon, a dome or head resting upon said ring, said dome or head having an interior reflecting surface, a lamp inside said casing connecting with said ring, a reflector having one or more reflecting surfaces or faces so arranged that rays of light from said lamp falling upon the interior reflecting surface of the dome will be reflected and directed thereby onto the reflecting surface or surfaces of said reflector and thereby be cast to a point or points outside said casing, and means for attaching said reflector to said casing.

7. In a device of the character specified, a reflector having a plurality of reflecting surfaces or faces, a base support therefor comprising an annular ring, supporting webs extending crosswise said ring with slots therein, slides adjustably retained in said slots, arms joined to said 125 slides, and a ball and socket jointure joining each of said arms to the surfaces or faces of the reflector or means carrying the same, substantially as described.
